BAYONET

Melvin M. Johnson, Jr., Brookline, Mass., assignor to Melvin M. Johnson, Brookline, Mass., and said Melvin M. Johnson, Jr., and Edward E. Rice, Boston, Mass., as trustees of Johnson Patent Trust

Application April 26, 1941, Serial No. 390,478

11 Claims. (Cl. 42—86)

This invention relates to a bayonet for attachment to the forward end of a gun barrel and has for its objects to provide an attachment which is simple and economical in construction, which is reliable and durable in use, which permits quick attachment and detachment of the bayonet, which has a detent of extensive bearing surface for latching the bayonet on the firearm, which is light but strong and which is therefore particularly suited to firearms of the reciprocating barrel type.

For the purpose of illustration a typical embodiment of the invention is shown in the accompanying drawing in which:

Fig. 1 is a side view of a bayonet applied to the barrel of a military rifle;

Fig. 2 is a section on line 2—2 of Fig. 1;

Fig. 3 is a side view of a fitting permanently mounted on the barrel to receive the bayonet detachably;

Fig. 4 is a bottom plan view of the bayonet;

Fig. 5 is a bottom plan view of the rear end of the bayonet with the spring detent removed;

Fig. 6 is a section on line 6—6 of Fig. 5;

Fig. 7 is a rear elevation of the spring detent;

Fig. 8 is a bottom plan view of the spring detent; and

Fig. 9 is a side view of the spring detent.

The particular embodiment of the invention chosen for the purpose of illustration comprises a blade 1, a flat rearward extension 2 and a ring 3 formed in a single piece. The blade 1 has a central rib 4 extending lengthwise along the bottom and the ring 3 has an opening 5 to fit over the forward end of a gun barrel B. Mounted on the gun barrel at a short distance from its forward end is a ring 6 having a depending lug 7, the ring being held in position on the barrel by means of two pins 8. The sides of the depending lug 7 are provided with grooves 9 extending parallel to the axis of the gun barrel and the lower end of the lug is rounded at 11 to form a cam surface. At its rearward end the extension 2 is bifurcated by a slot 12 to form legs 13 adapted to straddle the lug 7 and fit in the grooves 9 as shown in Fig. 2. The extension 2 may also be provided with a rivet opening 14 and an opening 15 to reduce the weight of the bayonet. The rear ends of the legs 13 have depending lugs 17 for a purpose hereinafter described.

According to this invention the bayonet is detachably held in operative position on the gun barrel by means of a detent in the form of a leaf spring 18 which extends lengthwise of the bayonet along the under side of the extension 2. At

its forward end it is provided with an opening 19 to receive the rivet 20 and near its rearward end it is provided with an opening 22 to receive the depending end of the lug 7. On opposite sides of the opening 22 the spring has lateral ears 23 which extend upwardly and then outwardly on opposite sides of extension 2, these ears serving as grips for engagement by the thumb and finger in flexing the spring downwardly away from the extension 2. To limit this downward flexing one of the ears is provided with an in-turned portion 24 for engagement with the bottom of the recess 26 in the extension 2, the depth of the recess 26 determining the limit to which the spring may be flexed. At the rear of the opening 22 the spring is provided with lateral arms 27 which are bent inwardly, as best shown in Figs. 1, 2 and 7, to form abutments for engagement behind the lower end of the lug 7. At its rear end the spring is provided with a bent tongue 28 for engagement with the cam surface 11 on the lug 7.

To attach the bayonet the legs 13 are first slipped into the grooves 9 from the front and thereafter the ring 3 moves over the forward end of the barrel. As the bayonet moves to the rear the tongue 28 engages the cam surfaces 11 to flex the rear end of the spring downwardly out of the path of the lower end of the lug. When the bayonet reaches its rearmost position the forward end of the lug 7 seats against the forward end of the slot 12 and the abutment arms 27 snap up to the position shown in Figs. 1 and 2 behind the lower end of the lug. In this position the folded arms 27 lie in front of the depending lugs 17 on the rear ends of the legs 13, whereby the abutment arms are protected against accidental engagement which might unlatch the bayonet from the lug 7. To remove the bayonet from the barrel the rear end of the spring is flexed downwardly by grasping the ears 23 with the thumb and finger and pulling downward until the inturned ear 24 seats in the recess 26, and then sliding the bayonet forwardly.

From the foregoing it will be evident that the attachment is simple in construction and facile in operation. It will also be evident that, by virtue of the unique leaf-spring construction, the attachment is very compact and safe against accidental detachment from the barrel.

It should be understood that the present disclosure is for the purpose of illustration only and that this invention includes all modifications and equivalents which fall within the scope of the appended claims.

I claim:

1. A bayonet for attachment to a firearm having a grooved lug, the rear end of the bayonet being bifurcated to form legs adapted to slide rearwardly in grooves in opposite sides of the lug, and a leaf spring for detachably locking the bayonet to the lug, one end of the spring being attached to the bayonet and the other end having lateral arms folded inwardly to form an abutment which snaps behind the lug when the bayonet is moved to rearmost position.

2. A bayonet for attachment to a firearm having a grooved lug, the rear end of the bayonet being bifurcated to form legs adapted to slide rearwardly in grooves in opposite sides of the lug; a leaf spring extending lengthwise of the bayonet for detachably locking the bayonet to the lug, the forward end of the spring being attached to the bayonet and the rearward end having lateral arms folded rearwardly to form an abutment which snaps behind the lug when the bayonet is moved to rearmost position, and lugs on the rear end of the bayonet behind said folded arms to protect the arms against accidental engagement.

3. A bayonet for attachment to a firearm having a grooved lug, the rear end of the bayonet being bifurcated to form legs adapted to straddle the lug, at least one leg sliding rearwardly in a groove in the side of the lug, a leaf spring for detachably locking the bayonet to the lug, one end of the spring being attached to the bayonet and the other end having lateral arms folded inwardly to form an abutment which snaps behind the lug when the bayonet is moved to rearmost position, and ears projecting from the spring at opposite sides of the bayonet for manually unlocking the spring from the lug.

4. A bayonet for attachment to a firearm having a grooved lug, the rear end of the bayonet being bifurcated to form legs adapted to slide rearwardly in grooves in opposite sides of the lug, a leaf spring extending lengthwise of the bayonet for detachably locking the bayonet to the lug, the forward end of the spring being attached to the bayonet and the rearward end having an abutment which snaps behind the lug when the bayonet is moved to rearmost position, ears projecting from the spring at opposite sides of the bayonet for manually unlocking the spring from the lug, and an inturned ear engageable with said end for limiting the unlocking movement of the spring.

5. A bayonet for attachment to a firearm having a grooved lug, the rear end of the bayonet being bifurcated to form legs adapted to slide rearwardly in grooves in opposite sides of the lug, a leaf spring for detachably locking the bayonet to the lug, one end of the spring being attached to the bayonet and the other end having an opening to receive the end of said lug, lateral arms folded inwardly at the rear of the opening to form an abutment which snaps behind the lug when the bayonet is moved to rearmost position, the spring having a cam surface in the rear of the abutment to ride over the end of the lug when the bayonet is moved rearwardly in said groove, and lugs on the rear end of the bayonet behind said folded arms to protect the arms against accidental engagement.

6. For attachment to a firearm having a grooved lug projecting downwardly from the barrel, a bayonet comprising a blade and a horizontal bar extending rearwardly from the blade under the barrel, the rear end of the bar being

bifurcated to form legs adapted to straddle the lug, at least one leg sliding rearwardly in a groove in the side of the lug, and a leaf spring extending lengthwise of the bar parallel thereto on the under side thereof, the front end of the leaf spring being secured to the bar and the rear end having a shoulder to snap behind the lower end of said lug, the rear end of the spring riding under said lug and then snapping upwardly behind the lug to hold the bayonet in position, and at least one of said legs having a shoulder disposed behind a part of the spring to prevent rearward displacement of the spring relatively to the blade in response to rearward thrust on the spring.

7. For attachment to a firearm having a grooved lug projecting downwardly from the barrel, a bayonet comprising a blade and a horizontal bar extending rearwardly from the blade under the barrel, the rear end of the bar being bifurcated to form legs adapted to straddle the lug, at least one leg sliding rearwardly in a groove in the side of the lug, and a leaf spring extending lengthwise of the bar parallel thereto on the under side thereof, one end of the leaf spring being secured to the bar and the other free end having a shoulder to snap behind the lower end of said lug, the free end of the spring riding under said lug and then snapping upwardly behind the lug to hold the bayonet in position, and the spring having side flanges bent up along the edges of said bar to restrain lateral displacement of the spring relatively to the bar.

8. For attachment to a firearm having a grooved lug projecting downwardly from the barrel, a bayonet comprising a blade and a horizontal bar extending rearwardly from the blade under the barrel, the rear end of the bar being bifurcated to form legs adapted to straddle the lug, at least one leg sliding rearwardly in a groove in the side of the lug, and a leaf spring extending lengthwise of the bar parallel thereto on the under side thereof, one end of the leaf spring being secured to the bar and the other free end having a shoulder to snap behind the lower end of said lug, the free end of the spring riding under said lug and then snapping upwardly behind the lug to hold the bayonet in position, at least one of said legs having a shoulder disposed behind a part of the spring to prevent rearward displacement of the spring relatively to the blade in response to rearward thrust on the spring and the spring having side flanges bent up along the edges of said bar to restrain lateral displacement of the spring relatively to the bar.

9. For attachment to a firearm having a grooved lug projecting downwardly from the barrel, a bayonet comprising a blade and a horizontal bar extending rearwardly from the blade under the barrel, the rear end of the bar being bifurcated to form legs adapted to straddle the lug, at least one leg sliding rearwardly in a groove in the side of the lug, means at the forward end of the bar for sliding engagement with the firearm, and a leaf spring extending lengthwise of the bar parallel thereto on the under side thereof, the front end of the leaf spring being secured to the bar and the rear end having an opening to receive the lower end of said lug, the rear of the spring riding under said lug and then snapping upwardly over the lug to hold the bayonet in position, and at least one of said legs having a shoulder disposed behind a part of the spring to prevent rearward displace-

ment of the spring relatively to the blade in response to rearward thrust on the spring.

10. For attachment to a firearm having a grooved lug projecting downwardly from the barrel, a bayonet comprising a blade and a horizontal bar extending rearwardly from the blade under the barrel, the rear end of the bar being bifurcated to form legs adapted to straddle the lug, at least one leg sliding rearwardly in a groove in the side of the lug, means at the forward end of the bar for sliding engagement with the firearm, and a leaf spring extending lengthwise of the bar parallel thereto on the under side thereof, the front end of the leaf spring being secured to the bar and the rear end having an opening to receive the lower end of said lug, the rear end of the spring riding under said lug and then snapping upwardly over the lug to hold the bayonet in position, and the spring having side flanges bent up along the edges of said bar to restrain lateral displacement of the spring relatively to the bar.

11. For attachment to a firearm having a grooved lug projecting downwardly from the bar-

rel, a bayonet comprising a blade and a horizontal bar extending rearwardly from the blade under the barrel, the rear end of the bar being bifurcated to form legs adapted to straddle the lug, at least one leg sliding rearwardly in a groove in the side of the lug, means at the forward end of the bar for sliding engagement with the firearm, and a leaf spring extending lengthwise of the bar parallel thereto on the under side thereof, the front end of the leaf spring being secured to the bar and the rear end having an opening to receive the lower end of said lug, the rear end of the spring riding under said lug and then snapping upwardly over the lug to hold the bayonet in position, at least one of said legs having a shoulder disposed behind a part of the spring to prevent rearward displacement of the spring relatively to the blade in response to rearward thrust on the spring and the spring having side flanges bent up along the edges of said bar to restrain lateral displacement of the spring relatively to the bar.
